This invention relates to a method of producing hydrazine hydrate, and more specifically is concerned with a method of preparing hydrazine hydrate from ketazines and hydrazones, particularly from dimethyl ketazine and acetone hydrazone.

It is known that in the production of hydrazine by the Raschig synthesis, solutions with a hydrazine content of only 1 to 2% are obtained. Furthermore, the yield is only in the region of 40 to 60%. It is also known that when bleaching liquor is reacted with ammonia and simple ketones, aqueous ketazine solutions are obtained in yields of more than 90% without the use of high pressures and temperatures, and that some of these solutions, for example in the case of dimethyl ketazine, have a lower boiling point than water and thus provide an extremely economical concentration of hydrazine in combined form. It is known that these ketazines can be split into hydrazine salt and ketone by acid hydrolysis. This hydrazine salt can, moreover, be worked up by various methods to hydrazine hydrate. Processes are also known, the object of which is to obviate this tedious and costly roundabout method by way of the salts and which permit the hydrate to be produced directly from ketazine solutions. However, all these proposals have basic defects which have prevented them from being carried out industrially.

Briefly described the method of the present invention comprises effecting a decomposition of the dimethyl ketazine and the acetone hydrazone into acetone and hydrazine by fractionating distillation at excess pressure and at a sump-temperature range between 100° to 250° C., said excess pressure being of about 1 to about 50 atmospheres.

If aqueous ketazine or hydrazone solutions are fractionated under high pressure and at high temperature, a splitting into ketone and hydrazine takes place hydrolytically, this permitting practically all the ketone to be removed at the top of the column. On the other hand, if the distillation is carried out under otherwise identical conditions at normal pressure, such a large excess of water is necessary to displace the hydrolytic equilibrium to effect the complete removal of the ketone that the process becomes completely uneconomical. Pressures of 1 to 50 and preferably of 1.5 to 20 atmospheres have proved to be suitable in practice.

Especially the decomposition of the ketazine and the hydrazone is effected in an aqueous medium containing about 19 to 25 percent of acetone and about 9 to 12 percent of hydrazine hydrate. Still more particularly the temperature range is between 130 to 210° C. and the excess pressure is from about 5 to 15 atmospheres.

Illustrative examples of ketazines and hydrazones are dimethyl ketazine and acetone hydrazone, represented by the following formulae:

2

and

5 The present invention provides a new and improved method of producing hydrazine hydrate in an economic manner, said method has the advantage of simplicity and avoids the necessity for using complicated apparatus techniques.

10 The following examples are given by way of illustrating and showing how the present invention can be carried into effect.

Example 1

15 To a column provided with filler bodies and being under a pressure of 9 atm. are supplied continuously 100 litres per hour of an aqueous solution of dimethylketazine containing 24.5% of acetone and 10.5% of hydrazine hydrate. The sump-temperature amounts to 178° C. 25 litres of a solution containing 94% of acetone and 2.0% of hydrazine hydrate were removed every hour at the top of the column. The composition of the sump material constantly removed was 0.2% of acetone and 13.0% of hydrazine hydrate. By concentration to high-percentage hydrazine hydrate, an acetone-free product was obtained.

Example 2

30 An aqueous solution of dimethyl-ketazine containing 9% hydrazine hydrate and 21.9% acetone is fractionated continuously in a column provided with filler bodies at a pressure of 4 atm. The run-in amounts to 80 litres per hour. From the top of the column there have been withdrawn 18 litres per hour of a solution containing 91% acetone and 2.3% of hydrazine hydrate. The sump-temperature amounts to 145° C. The analytical result of the sump-running off shows 10.8% of hydrazine hydrate and 0.8% of acetone.

Example 3

35 An aqueous solution of dimethyl-ketazine containing 24.5% of acetone and 10.5% of hydrazine hydrate is fractionated continuously in a column having filler bodies at a pressure of 20 atm. and at a sump-temperature of 216° C. The run-in amounts to 125 litres per hour. At the top of the column there are withdrawn 30 litres per hour of a solution containing 96% of acetone and 1.5% of hydrazine hydrate. The composition of the sump-running off is 0.1% of acetone and 12% of hydrazine 50 hydrate.

Example 4

40 An aqueous solution of acetone hydrazone containing 10.4% of acetone and 11.1% of hydrazine hydrate is fractionated in a column with filler bodies at a pressure of 4 atm. and at a sump-temperature of 146° C. The run-in amounts to 100 litres per hour and the run off to 10.8 litres per hour, containing 93.0% of acetone and 1.8% of hydrazine hydrate. The sump-running off contains 0.3% of acetone and 12.1% of hydrazine hydrate.

Example 5

45 An aqueous solution of acetone hydrazone containing 21.0% of acetone and 12.3% of hydrazine hydrate is fractionated continuously in a column with filler bodies at a pressure of 20 atm. and at a sump-temperature of 216° C. The run-in amounts to 125 litres per hour and the run off at the top of the column to 26 litres per hour. The run off contains 96.2% of acetone and 1.3% of hydrazine hydrate. The sump withdrawn continuously 50 shows the following compounds: 0.1% of acetone and 14.3% of hydrazine hydrate.

We claim:

1. A process for the production of hydrazine hydrate which comprises decomposing a hydrazine compound selected from the group consisting of dimethyl ketazine and acetone hydrazine in the form of an aqueous solution thereof by fractionally distilling such a solution under a pressure of between 2 atmospheres and 50 atmospheres and at a sump temperature ranging between 120 and 250° C.

2. Process according to claim 1 wherein said sump temperature range is from 130 to 210° C.

3. Process according to claim 1 wherein said pressure is from about 5 to 15 atmospheres.

4. Process according to claim 1 wherein said aqueous solution of said group member additionally contains about 19-25% of acetone and about 9-12% of hydrazine hydrate.

5. A process for the production of hydrazine hydrate which comprises decomposing dimethylketazine in the form of an aqueous solution thereof which solution additionally contains 24.5% of acetone and 10.5% of hydrazine hydrate by fractionally distilling such solution under a pressure of 9 atmospheres and at a sump temperature of about 178° C.

6. A process for the production of hydrazine hydrate which comprises decomposing dimethylketazine in the form of an aqueous solution thereof which solution additionally contains 21.3% acetone and 9% hydrazine hydrate by fractionally distilling such solution at a pres-

sure of 4 atmospheres, and at a sump temperature of 145° C.

5 7. A process for the production of hydrazine hydrate which comprises decomposing dimethylketazine in the form of an aqueous solution thereof which solution additionally contains 24.5% of acetone and 10.5% of hydrazine hydrate by fractionally distilling such solution at a pressure of 20 atmospheres, and at a sump temperature of 216° C.

10 8. A process for the production of hydrazine hydrate which comprises decomposing acetone hydrazone in the form of an aqueous solution thereof which solution additionally contains 10.4% of acetone and 11.1% of hydrazine hydrate by fractionally distilling such solution at a pressure of 4 atmospheres and at a sump temperature of 145° C.

15 9. A process for the production of hydrazine hydrate which comprises decomposing acetone hydrazone in the form of an aqueous solution thereof which solution additionally contains 21.0% of acetone and 12.3% of hydrazine hydrate by fractionally distilling such a solution at a pressure of 20 atmospheres, and at a sump temperature of 216° C.
